(57) **CLAIM**

The ornamental design for a dispenser for a roll good, as shown and described.

DESCRIPTION

FIG. 1 is a perspective view of the dispenser for a roll good; FIG. 2 is a top view thereof; FIG. 3 is a front view thereof; FIG. 4 is a left side view thereof; FIG. 5 is a right-side view thereof; FIG. 6 is a rear view thereof; FIG. 7 is a bottom view thereof; and, FIG. 8 is a perspective view thereof in use.

The portions of the dispenser for a roll good in FIGS. 1-8 shown in broken lines are included to show features that form no part of the claimed design. Additionally, the broken lines shown in FIG. 8, showing a roll of goods depict the environmental structure, and forms no part of the claimed design.
